(57) CLAIM

The ornamental design for a portable work bench, as shown and described.

DESCRIPTION

FIG. 1 is a front perspective view of an embodiment of a portable work bench showing our new design, with support arms in retracted position.

FIG. 2 is a left side elevational view.

FIG. 3 is a right side elevational view.

FIG. 4 is a front elevational view.

FIG. 5 is a rear elevational view.

FIG. 6 is a top plan view;

FIG. 7 is a bottom plan view; and,

FIG. 8 is a front perspective view with the support arms in extended position.

1 Claim, 4 Drawing Sheets

FIG. 1

FIG. 2

FIG. 3

FIG. 4

FIG. 5

FIG. 6

FIG. 7

FIG. 7 is a perspective view of a rectangular frame structure. The frame is made of a dark, textured material, possibly wood or metal. It features a central horizontal beam supported by vertical legs. A diagonal support rod is attached to the top-left and bottom-right corners of the frame. The entire structure is set against a solid black background.

FIG. 8

FIG. 8 is a perspective view of a rectangular frame structure. The frame is made of a light-colored, smooth material, possibly wood or metal. It features a central horizontal beam supported by vertical legs. A diagonal support rod is attached to the top-left and bottom-right corners. The entire structure is set against a solid black background.
